UNITED STATES PATENT OFFICE

90,510

DESIGN FOR AN AUTOMOBILE MAT

Roy H. Schwartz, Cleveland, Ohio

Application May 8, 1933. Serial No. 48,035

Term of patent 7 years

To all whom it may concern:

Be it known that I, Roy H. SCHWARTZ, a citizen of the United States, residing at Cleveland, in the county of Cuyahoga and State of Ohio, have invented a new, original, and ornamental Design for an Automobile Mat, of which the following is a specification, reference being had to the accompanying drawing, forming part thereof.

I claim:

The ornamental design for an automobile mat, as shown and described.

ROY H. SCHWARTZ.
